UNITED STATES PATENT OFFICE.

LAWRENCE E. HARRIS, OF SUPERIOR, WYOMING.

SAFETY HANGER FOR BRAKE BEAMS.

Application filed March 2, 1926. Serial No. 91,739.

My present invention pertains to safety hanger means for the brake beams of railway rolling stock and it consists in the peculiar and advantageous construction for the purpose indicated, as hereinafter described and definitely claimed.

In the accompanying drawings, forming part of this specification:—

Figure 1 is a view in side elevation illustrating my novel construction as properly applied relative to a brake beam and the bolster of a truck of a railway car.

Figure 2 is an enlarged perspective of the bracket support of my improvement and the keeper carried by said support.

Figure 3 is a fragmentary enlarged perspective taken substantially at right angles to Figure 1 and showing the hanger member as properly arranged relative to the bracket support and the brake beam, the latter being illustrated by dotted lines.

Similar numerals of reference designate corresponding parts in all of the views of the drawings.

I show in Figure 1 one of the wheels 1 of a railway car in proper association with a truck 2 and a brake beam 3, the latter being equipped with the conventional or any other suitable shoes 4 one of which is shown in proper relative arrangement to the wheel 1.

The bolster of the truck 2 is designated by 5, and in accordance with my invention a bracket support 6 is superposed on the bolster 5 and is fixedly or pivotally connected thereto as designated by 7, as may be deemed most expedient by the manufacturer.

The bracket support 6 is in the form of a plate and is extended from the bolster 5 toward the wheels, and is provided in its end adjacent to the wheels with a longitudinal notch 8. Disposed below and pivotally connected to the notched portion of the bracket support 6 is a keeper 9, preferably of right angle form, pivotally connected at 11 to the bracket support and designed to be detachably secured in the closed position shown in Figures 2 and 3 through the medium of a cotter pin 10 or any other reliable device.

The hanger member of my improvement is designated by 12 and is provided with a shank and with a loop, the latter being designated by 13 and having its terminal portion so disposed, Figure 1, that the mouth of the loop is substantially closed, and hence there is no liability of the brake

beam 3 being casually released from the loop after the same is once fitted about the brake beam. Manifestly my invention contemplates the arrangement of the hanger member 12 in engagement with an intermediate portion of the beam 3, that is to say, a portion of the beam 3 between the shoes ordinarily carried thereon. The shank of the hanger member 12 is provided at its upper end with a head 14 and immediately below the said head 14 the shank is provided with a reduced portion 15 of angular cross-section which is designed to be arranged in the notch 8 with a view to precluding turning of the shank of the hanger member about its axis.

It will be apparent from the foregoing that my novel construction may be depended upon to preclude casual falling of the brake beam 3 and its appurtenances in the event of the usual swingable hanger means 16 of the brake beam being broken or loosened or impaired. It will also be appreciated that my novel construction is simple and inexpensive, and lends itself to ready installation, and renders it feasible to quickly and easily remove the brake beam 3 and its appurtenances when such removal is desirable or necessary.

While I prefer the construction herein illustrated and described, I do not desire to be understood to be limiting myself to the precise structure and relative arrangement of the parts comprised in the improvement, my invention being defined by my appended claims within the scope of which modifications in structure and in arrangement may be made without departure from my invention.

Having described my invention, what I claim and desire to secure by Letters-Patent, is:—

1. In safety hanger means for brake beams and in combination, a brake beam, a truck having a bolster, a bracket support superposed upon and connected to the bolster and extending beyond the same and having in the end of its extended portion a longitudinally disposed notch, a right angle keeper pivotally connected to the bracket support and apertured adjacent to its free end, a device extending through the keeper and the bracket support and detachably securing the keeper in a position across the mouth of the notch, and a hanger member having a loop receiving the brake beam and

also having a shank with a head at its upper end and with a portion immediately below said head, of angular cross-section, and disposed in the notch or the bracket support whereby the hanger member is held against turning about the axis of its shank.

2. Safety hanger means for brake beams, comprising a bracket support with a notch in one end thereof, a keeper carried by said bracket support and equipped to be secured in a position across the mouth of the notch so as to close said notch, and a hanger member having a loop to receive a brake beam and also having a shank headed at its upper end and provided below said end with a portion adapted to be placed in the notch of the bracket support.

3. In safety hanger means for brake beams, and in combination, a truck, a brake beam, a bracket support carried by and extending laterally from a portion of the truck and having a notch in the end of its

extended portion, a hanger member shaped to receive the brake beam and having a shank removably disposed in the end notch of the bracket support and also having a head superposed upon said support, and means for retaining the shank of the hanger member in the notch of the bracket support.

4. Safety hanger means for brake beams comprising a notched bracket support, a hanger member having means to receive a brake beam and also having a shank for removable arrangement in the notch of the bracket support and means to bear on said support and hold the hanger member against downward movement relative to the support, an adjustable keeper carried by the bracket support for retaining the shank of the hanger member in the notch of the support, and means for detachably securing said keeper in closed position.

In testimony whereof I affix my signature.

LAWRENCE E. HARRIS
